CALCULATOR WITH SLIDING TAMBOUR COVER

Karl T. Baughman, Lake Forest, Ill., assignor to
Sears, Roebuck and Co.

Filed Apr. 8, 1974, Ser. No. 458,780

Term of patent 14 years

Int. Cl. D18—01

U.S. Cl. D26—5 C

Fig. 1.

FIG. 3.

Fig. 4

FIG. 1 is a top perspective view of a calculator with sliding tambour cover showing my new design, with the tambour cover in open position;

FIG. 2 is a bottom perspective view thereof rotated 180° from the position illustrated in FIG. 1;

FIG. 3 is a top plan view thereof rotated 180° from the position illustrated in FIG. 1; and

FIG. 4 is a top plan view thereof with the tambour cover in closed position.

I claim:

The ornamental design for a calculator with sliding tambour cover, as shown and described.
